UNITED STATES PATENT OFFICE.

HENRY J. GAISMAN, OF NEW YORK, N. Y.

WAIST-BELT.

No. 827,859.

Specification of Letters Patent.

Patented Aug. 7, 1906.

Application filed February 28, 1899. Serial No. 707,176.

To all whom it may concern:

Be it known that I, HENRY J. GAISMAN, a citizen of the United States, residing in New York city, county and State of New York, have invented certain new and useful Improvements in Waist-Belts, of which the following is a specification.

My invention relates more particularly to improvements in the means for attaching a waist-belt to a device or devices on a garment; and to this end the invention consists in a waist-belt provided with means for connecting it together around a waist and having a pair of transverse strips attached to its inner face and a bar or the like connected with said strips and having a free space for connection with a complementary device on a garment.

The invention also consists in the novel details of improvement and the combinations of parts that will be more fully herein-after set forth and then pointed out in the claims.

Reference is to be had to the accompanying drawings, forming part hereof, wherein—

Figure 1 is a perspective view of a waist-belt embodying my invention. Fig 2 is an inner face view of a belt embodying my invention and particularly adapted for women's use. Fig. 3 is a similar view showing the attaching-bar in a single piece or strand. Fig. 4 is an enlarged cross-section on the line 4 4 in Fig. 2. Fig. 5 is an enlarged cross-section on the line 5 5 in Fig. 3. Fig. 6 is an enlarged cross-section on the line 6 6 in Fig. 2, showing the attaching-bar connected with a hook on a garment. Fig. 7 is a detail face view showing the slotted attaching-bar connected with the cross-strip by the means shown in Figs. 3 and 5. Fig. 8 is a section on the line 8 8 in Fig. 7. Fig. 9 is a section on the line 9 9 in Fig. 7. Fig. 10 is a detail face view of the belt and its attaching slotted bar, showing means carried by the latter to keep the two arms of the bar from spreading apart. Fig. 11 is a cross-section on the line 11 11 in Fig. 10. Fig. 12 is a detail of the receiving end of the attaching-bar shown in Fig. 10, and Fig. 13 is a detail of the device for keeping the arms of the slotted bar from spreading.

In the accompanying drawings, in which similar characters of reference indicate corre-

sponding parts in the several views, 1 indicates a waist-belt which may generally be of any suitable construction, being shown provided with a fastener or buckle 2 for connecting its ends together around a waist in well-known manner. In Fig. 1 the belt shown is of the type having a plurality of strap-like parts connected together by interposed rings 3 and which is particularly adapted for men's use, while in Figs. 2 and 3 the belt is shown in a single strip, such as usually used by women.

On the inner face of the belt I place two strips 4 5, which extend transversely of the belt and are secured to the latter, preferably at or near their ends and by preference by stitches 6, that pass through said strips and through the belt. When the longitudinal edges of the belt have rows of stitches, I may utilize those stitches in attaching the strips 4 5 to the belt. Said strips may be made of leather or other suitable material and preferably extend to or close to the edges of the belt. The strips 4 5 are arranged in one or more pairs and serve as supporting or intermediate means for connecting a bar 7 to the belt. The bar 7 is attached at or near its ends to the strips 4 5, which may be accomplished in any suitable manner. The bar 7 is adapted to be attached to a complementary device—such as a hook, button, or the like 8—on a garment 9, (seen in Fig. 6,) so as to retain the belt in proper position relatively to the garment. In some cases the bar 7 is provided with a slot 7^a, adapted to receive the shank of a button on the garment; but where a button is not used the bar may be slipped under a hook 8, attached to the garment, as in Fig. 6.

In Figs. 1, 2, and 10 the strip 4 is shown provided with eyelets 10 to receive the two adjacent ends of the bar or attaching device 7, and the strip 5 has an eyelet 11 to receive the opposite end of bar 7. This arrangement gives the user the selection of different types of complementary attaching devices on a garment.

In Figs. 3 and 5 the bar 7 is in a single piece of strand between the strips 4 5, and it is adapted to be slipped under a hook 8 to connect the belt with the garment in manner similar to that shown in Fig. 6. The bar 7 may be attached to the strips 4 5 in any suit-

able manner. I have shown a plate or strip 12, having an eye 13 to receive the end of the bar. The plates or strips 12 are located between the belt and the strips 4 5, and the eyes 13 project through apertures in strips 4 5 in position to receive the ends of the bar 7. The bar 7 may be secured to the eyes 13, as by upsetting the ends of the bar or by closing in the outer ends of the eyes.

10 In Figs. 7 and 8 the attaching-bar 7, instead of being connected to the strips 4 5 by means of eyelets, is connected to said strips by means of the plates 12, having eyes 13. In this case the two arms of the bar 7 at one end 15 project sidewise at 7^b and forwardly at 7^c, the latter parts passing into or through the eyes 13. There may be two of such eyes formed in one plate 12 or separate plates each having an eye arranged in manner similar to that 20 shown in Fig. 5. In Fig. 7 one of the arms of the attaching-bar 7 is shown provided with an inward bend at 7^d at the open end of slot 7^a to prevent the shank of a button from spontaneously passing out of said slot. The 25 opposite end of bar 7 is shown connected with a plate 12, having an eye 13; but in this case the eye 13 is formed by striking up a tongue from plate 12 and then rolling the same over the end cross-arm 7^e of bar 7.

30 In assembling the parts the tongue of plate 12 is passed through an opening in strip 5 and left in this position, as shown in Fig. 9, until the ends 7^e of bar 7 are passed through eyes 13, that project through strip 4, and as the 35 ends 7^e of bar 7 can thus pass through eyes 13 a relatively loose or sliding connection is made between the bar at one end and the transverse strip, and the cross-arm 7^e is next slipped under the hook so formed at the strip 40 5, as shown in Fig. 9, and then the eye is closed down around said arm 7^e, as shown in Fig. 8, providing a relatively firm or immovable connection between the bar at such end and the transverse strip, all to retain the attaching-bar on the belt. This arrangement 45 provides a convenient means for securing the attaching-bar 7 to the strips 4 5. Such loose or sliding connection between the bar and the belt permits the latter to be drawn snugly 50 around a waist without restraint from the bar.

In order to prevent the button on the garment from slipping under the strip 4 when the button is being released from the holding-bar 7, I preferably cut out one edge of said strip at 4^a in such manner as to allow the button-shank to pass away from the slot 7^a of bar 7 without allowing the button itself to slip under the strip 4. (See Fig. 7.)

60 In Figs. 10 and 11 the strips 4 5 instead of being in separate pieces are shown made integral with an intermediate strip 5^a, that is preferably wider than the attaching-bar 7, but does not extend to the edges of the belt.

With this arrangement the button is prevented from slipping under the cross-strip 4 when being detached from the slot 7^a of bar 7.

When the attaching-bar 7 is made with two arms *a b* to provide the slot 7^a and such bar is made long and of light wire, there 70 might be danger that the arms would spread apart, and thus allow the button to become detached from the bar. In order to prevent this, I provide the following arrangements: Near the open end of slot 7^a the arms *a b* on 75 their outer edges are provided with inwardly-extending depressions or bends *c d*, and upon these arms I mount a button-holding device A, which has at one end a slot A', leading to its socket A², and said button-holder is shown 80 provided with eyes A³ A⁴, respectively, adapted to receive the arms *a b* of the attaching-bar 7. (See Figs. 10 and 11.) By preference this button-holder is made of wire, and the eyes A³ A⁴ are substantially at right 85 angles to the socket A². The distance between the eyes A³ A⁴ is such that when they come in line with the depressions *c d* in arms *a b* they will enter the same, and thus retain the button-holder near the open end of slot 90 7^a. When the belt is to be attached to a button on a garment, the shank of the button is first slipped through slot A' into socket A² in the button-holder, and owing to the presence of the eyes A³ A⁴ in the depressions *c d* the 95 button-holder will remain in position until the button-shank passes into socket A² and against the end of the button-holder. Thereupon as the belt is pulled the pressure will 100 cause the button-holder to slip from the depressions *c d* and pass along the arms *a b* to the desired position; but the presence of the button-holder upon said arms prevents them 105 from spreading apart in line with the button, so that the button cannot become detached from the attaching-bar 7 by slipping out from between the arms *a b*. When the belt is to be removed, it is pulled until the eyes of the button-holder A reach the depressions *c d* of arms *a b*, whereupon it will stop, and then 110 the shank of the button by a continued pull on the belt will pass away from said button-holder. The particular form of button-holder shown may be varied so long as the idea is retained of having the button-holder 115 adapted to receive the shank of a button and to slide along the arms *a b* with the button and to keep said arms from spreading apart.

It will be seen that the bar 7 is at a distance or raised from the inner face of the belt, 120 so as to allow the button, hook, or the like when attached to the bar to lie between the bar and the belt.

In either example illustrated the bar 7 between the strips 4 5 presents a free space 125 along which the button, hook, or other complementary device on the garment can be adjusted, or, in other words, when the bar 7 is

connected with such button, hook, or the like the belt can be adjusted around the waist to bring the front fastener to the proper position, while the parts 7 8 remain in connection. When the belt is adjusted to the waist and the parts 7 and 8 are connected, as stated, the belt and the garment to which it is attached remain in position relatively to each other.

- 10 When my improvements are applied to men's belts, a bar 7, with its pair of attaching-strips 4 5, is placed at each side of the front opening of the belt, as shown in Fig. 1, and can thus be connected with the buttons 15 on the waistband of the trousers or, if preferred, with hooks attached to such waistband. When the belt is to be made for women's use, a single bar 7 and the pair of strips 4 5 are preferably placed at the central 20 back portion of the belt, and a hook or button is attached to the garment at the back—as, for instance, upon the waistband of a skirt—and thus the skirt-band is kept from slipping below the belt, and the belt is kept 25 from slipping above the skirt-band.

It is evident that the bar 7 can be constructed otherwise than as shown, and I do not limit my invention to the precise details of construction shown and described, as it 30 may be varied without departing from the spirit thereof.

Having now described my invention, what I claim is—

1. A waist-belt provided with means for 35 connecting its ends together and having a pair of transverse strips attached to its inner face, and a bar or the like connected with said strips and located at a distance from the belt to provide a free space for receiving a 40 complementary device on a garment, substantially as described.

2. A waist-belt provided with means for connecting its ends together and having a pair of transverse strips spaced apart and attached near their ends to the belt, and a bar or the like connected with said strips and having a space between said strips for connection with a complementary device on a garment, the bar being located at a distance from 45 50 the belt to receive such device between the belt and the bar, substantially as described.

3. A waist-belt provided with means for connecting its ends together and having a pair of transverse strips attached to its inner 55 60 face, and a bar connected with said strips and having a slot adapted to receive a complementary device on a garment, said strips acting to hold the bar at a distance from the belt to provide a space between the belt and 65 70 a bar for a holding device on a garment, substantially as described.

4. A waist-belt provided with means for connecting its ends together and having a

pair of transverse strips attached to its inner face, and a bar having a slot, the two adjacent ends of the bar being attached to one strip and the opposite end attached to the other strip, said bar being maintained by the strips at a distance from the belt providing a space to receive a complementary device on a garment, substantially as described. 65 70

5. A waist-belt, provided with means for connecting its ends together, an attaching-bar, a plate having an eye or eyes to receive the corresponding end of the attaching-bar, 75 and a strip attached to the belt and overlying the plate, the eye projecting through said strip, substantially as described.

6. A waist-belt provided with means for connecting its ends together and having a 80 pair of transverse strips attached to its inner face, a plate or strip located between the belt and the corresponding transverse strip and having an eye projecting through an aperture in such strip, and a bar having its end 85 located in said eye, said bar being adapted for connection with a complementary device on a garment, substantially as described.

7. A waist-belt provided with means for connecting its ends together, an attaching-bar having two arms provided with a slot between them, plates having eyes to receive the ends of said arms, and a strip overlying each plate and attached to the belt, substantially as described. 90 95

8. A waist-belt provided with means for connecting its ends together, an attaching-bar having two arms provided with a slot between them open at one end, said arms being bent sidewise and then outwardly at one end, 100 plates having eyes to receive the ends of said arms, and a strip overlying each plate and attached to the belt, substantially as described.

9. A waist-belt provided with means for 105 connecting its ends together, an attaching-bar having two arms provided with a slot between them, a plate having eyes to receive one end of said bar, and a plate at the other end of the bar having an eye formed by a 110 tongue struck up from the plate and adapted to be folded over the end of the bar, and a strip overlying each plate and attached to the belt, substantially as described.

10. A waist-belt provided with means for 115 connecting its ends together, an attaching-bar having a slot open at one end, and a pair of strips attached to the belt and also attached to the ends of said bar, one of said strips having a cut-out part in line with the 120 open end of the slot of the bar, substantially as described.

11. The combination with a belt, of a 125 waist-button-attaching device located along the inside of the belt, the said belt and attaching device being secured immovably to

gether at one point and having a sliding connection with each other at another point, substantially as described.

12. The combination with a belt having a pair of cross-straps spaced apart and secured thereto, of a waist-button-attaching device having one end secured rigidly to one of the

cross-straps and having its other end loosely secured to the other cross-strap, substantially as described.

HENRY J. GAISMAN.
